ROTARY COMPRESSOR

Ralph E. Lamberton, Worthington, and Orville R. Lowther and Robert A. Redding, Columbus, Ohio, assignors to The Jaeger Machine Company, Columbus, Ohio, a corporation of Ohio

Filed Sept. 5, 1963, Ser. No. 306,952

13 Claims. (Cl. 230—26)

Our invention relates to a rotary compressor. It deals, more specifically, with an unloading system for a rotary compressor whereby the power required to drive the compressor while it is running in an unloaded state is greatly reduced as compared to power requirements of prior art compressors in a similar state.

This invention deals mainly with compressors of the internally oil-cooled, sliding-vane rotor, positive-displacement type. It is applicable, particularly, to a rotary compressor of this general type which is driven by an electric motor although it is not necessarily limited to an electrically-driven compressor.

At the present time, compressors of the general type indicated are provided with unloading systems but by these systems only the intake valve of the compressor is closed so that atmospheric air to be compressed will not be taken into the compressor and a very high vacuum will result at the intake side of the compressor unit. The rotor continues to rotate in the unloaded state of the compressor, even if there is no need to compress air, to provide for proper circulation of the relatively large volume of lubricating-cooling oil in the system. However, even in the unloaded state, the rotor is working against the pressure in the air receiver which is reflected back to the discharge chamber of the high-pressure cylinder. Since no air is entering the low-pressure cylinder, all sectors of both rotors bounded by the sliding vanes are operating at a partial vacuum. As each sector of the high-pressure rotor is exposed to this receiver backpressure, air expands into this cavity and must be recompressed back to a pressure slightly greater than that of the receiver, as the rotor vanes pass the discharge port. This alternate expansion and recompression results in a high power consumption for driving the rotor in the unloaded state of the compressor as compared to the power consumption required to drive it in the loaded state. This is particularly true of the electrically-driven compressors, in which the electric motor drives at constant speed. Even in connection with rotary compressors driven by internal combustion engines, where the throttle is moved to a minimum speed position during the time the compressor is unloaded, a substantial amount of power and, therefore, fuel is required to drive the rotor while the compressor is unloaded.

It is the main object of this invention to provide an unloading system for a compressor of the type indicated which may be termed a "free" unloading system in that the rotor will not be required to work against the pressure of the compressed air in the receiver part of the compressor unit and, therefore, the amount of power required to drive the rotor during that unloaded state will be a minimum.

Another object of our invention is to provide a free-unloading system of the type indicated in an internally, oil-cooled compressor wherein an unloading point is selected in the system where the air is sufficiently free of circulating lubricating-cooling oil to allow it to be exhausted to the atmosphere without excessive loss of oil.

Another object of our invention is to provide a control system for a compressor of the type indicated which preferably will automatically control starting and stopping

2

of the compressor as well as loading and unloading of the compressor in accordance with our invention.

A further object of our invention is to provide a free-unloading system of the multi-stage type wherein an interstage manifold connects the stages of the compressor having an oil-scavenging system associated therewith for preventing the accumulation of excessive amounts of oil in the manifold while the compressor is operating in the unloaded state.

Various other objects will be apparent as this description progresses.

In the accompanying drawings, we have illustrated one embodiment of our invention, the embodiment shown being a compressor which is electrically driven, but it is to be understood that many specific variations are possible without departing from basic principles of our invention.

In these drawings:

FIGURE 1 is a schematic diagram of the fluid system of a rotary compressor embodying our invention with certain electrical members indicated in association therewith.

FIGURE 2 is a schematic diagram of the electrical system used on the compressor in accordance with our invention.

FIGURE 3 is a view illustrating details of the oil-scavenging system associated with the free-unloading system.

With reference to the drawings, in FIGURE 1 we have illustrated schematically a rotary compressor system to which our invention is applicable, but it is to be understood that we are not limited to this specific compressor system. The structure of the rotary compressor itself may be generally like that disclosed in the patent to Lamberton No. 2,739,758 issued March 27, 1956, but its drive is shown herein as being an electric motor. The general arrangement and positioning of the various units of the compressor system may be similar to that disclosed in the copending application of Paugh Ser. No. 215,390, filed August 7, 1962, now U.S. Patent 3,156,409.

In FIGURE 1, we indicate a compressor 10 of the rotary type which is driven by an electric motor indicated at 11. The compressor may be of the multi-stage type and is shown as having a low-pressure cylinder 12 and a high-pressure cylinder 13. These cylinders are connected together by an interstage manifold 14 so that low-pressure air discharged from the cylinder 12 will be conducted into the cylinder 13 for further compression. The low-pressure cylinder 12 houses a rotor (not shown) preferably of the sliding vane type which is coupled to and is driven by the motor 11. The rotor in the low-pressure cylinder is coupled to and drives the rotor (not shown) which is in the high-pressure cylinder 13. The low-pressure cylinder 12 is provided with an air intake conduit 15 having a two-way unloading valve 16 connected therein which is of the piston type and is adapted to be actuated by air-pressure. A filter 17 is also provided for the intake conduit 15 so that air taken into the low-pressure cylinder 12 from the atmosphere will be filtered. Also connected to the filter 17 is an air conduit 18 which is adapted to inspirate air into the interstage manifold 14, to the low-pressure end of which it is connected as shown. This conduit 18 is provided with the check valve 19. The conduit 18 functions in a manner, to be described in detail later, to aid in preventing undue accumulation of oil in the manifold 14.

The high-pressure cylinder 13 is provided with an outlet or discharge chamber for the compressed air and oil mixture which connects by a discharge conduit 20 to the receiver tank, indicated at 21, and a check valve 22 is provided in this conduit. A thermally-actuated electric switch TH1 is also associated with the discharge conduit

20 as indicated, so as to be actuated by the temperature of the air and oil mixture discharged from the high-pressure cylinder 13. An oil reservoir tank is illustrated at 23 below the receiver tank 21 and is connected thereto. An air-oil separator is indicated at 24 above the tank 21 and is connected thereto. The separator 24 is connected to the air-service conduit 25 which has a check valve 26 therein and which supplies the air compressed by the compressor to the point of use. An oil bleeder conduit 27 leads from the lower portion of the separator 24 and connects to the low-pressure end of the manifold 14, being provided with a strainer 28 and a check valve 29, associated with a restricted passage to the manifold, connected therein in series. This conduit 27 functions to return the separated oil to the interstage manifold 14 and does it in a manner to aid in scavenging oil from the manifold as will be described in detail later.

Oil for lubrication and cooling is supplied by a pump 30 in the usual manner, this pump being coupled to the rotor in the cylinder 13. The discharge of this pump is connected by an oil conduit 31 to the oil supply system of the cylinders 12 and 13 which is indicated schematically as the gallery 32 and a flow switch FLS is interposed in this oil conduit 31 although a pressure switch may be used instead of this flow switch. The inlet side of the pump 30 is connected by an oil conduit 33 to an oil cooler indicated at 34 and a filter 35 is interposed in this conduit. Also, a thermally-actuated switch TH2 is associated with this conduit and is actuated by the temperature of the oil therein from the cooler 34. A blower is indicated at 36 as part of the oil cooler and is driven by an electric motor 37. An oil conduit 38 leads from the oil reservoir 23 to the oil cooler 34 through a thermally-actuated by-pass valve 40 which is actuated by the temperature of the oil coming from the tank 23. A by-pass oil conduit 39 is also connected to this valve 40 and connects to the oil conduit 33 leading from the oil cooler 34.

The pressure-actuated unloading valve 16 is connected by an air conduit 41 to a three-way solenoid actuated valve S2 which may be of the well-known spool type. The conduit 41 has a check-valve 42 therein and restricted bypass 43 passes around the check-valve. Leading from the valve S2 is an air conduit 44 which connects to an air conduit 45 through an air-liquid separator 46. A pressure-actuated electrical switch PS is connected to the conduit 45 and this conduit connects to the air service conduit 25 beyond the check-valve 26.

The unloading system according to our invention also includes an exhaust valve S1 which is connected to the oil separator 24 by a conduit 51. This valve S1 is a solenoid-actuated two-way valve. Its exhaust side is connected to an exhaust silencer 50 of a suitable type.

An electrical power and control circuit for operation of the compressor in accordance with this invention is diagrammatically illustrated in FIGURE 2. The control circuit, as illustrated, is adapted to not only automatically control operation of the compressor as to loaded and unloaded operation in accordance with service demands but to automatically start and stop the apparatus in accordance with predetermined operational conditions. It is the primary function of the control circuit to automatically operate the several components of the apparatus as to provide for free-unloaded operation of the compressor.

The electrical power circuit is connected to a three-phase, alternating current power distribution system of suitable voltage and includes the three power lines L1, L2 and L3. A three-pole disconnect switch 55 is interposed in the power lines along with the necessary overcurrent protective devices, such as the fuses 56. Connected to the power lines L1, L2 and L3 are the electric motors 37 and 11, previously referred to, for operating the oil cooler blower 36 and driving the rotary compressor 10. Each respective motor 11 and 37 is connected to the power lines through a magnetic contactor of the type having a set of normally open contacts, 1CR1, 1CR2 and 1CR3,

and 2CR1, 2CR2 and 2CR3, controlled by their respective electromagnetic solenoids 1CR and 2CR. Also incorporated in each magnetic contactor are the usual overload protective devices consisting of the associated thermally-responsive elements and normally closed contacts OL1, OL2, OL3 and OL4. As will be noted from the circuit diagram, the overload devices OL1 and OL2 are associated with the compressor motor 11 and the overload devices OL3 and OL4 are associated with the blower motor 37. Also connected to the power lines L1 and L3 is a control circuit voltage transformer 57 which provides the desired voltage for operation of the control circuit.

The control circuit includes a start-stop circuit having manually-actuated start and stop switches 58 and 59 which may be of the pushbutton type. The stop switch 59 is normally closed while the start switch 58 is normally open with the contacts of each being serially connected across the secondary output conductors of the transformer 57. Also connected in series with the switches 58 and 59 is the coil 3CR of a circuit-maintaining relay which by-passes the start switch 58, once the compressor apparatus has been started and is operating normally. Completion of the start and stop circuit is through a serially-connected, thermostatically-operated switch TH1, previously mentioned, and the normally closed contacts of the overload devices OL1 and OL2 associated with the compressor motor 11. The thermostatic switch TH1 is provided with a normally closed contact which will open when the temperature of the oil-air mixture discharged from the high-pressure stage 13 of the compressor exceeds a predetermined value. In this present embodiment, the switch TH1 is set to open at about 240° F. and will break the start-stop circuit, thus protecting the compressor apparatus from damage due to high temperatures. Serially connecting the contacts of the overload devices OL1 and OL2 in the start-stop circuit provides further protection for the compressor apparatus in the event that an overload should occur in the compressor motor 11. An overload of this form would also break the start-stop circuit deenergizing the control circuit and disconnecting the compressor and blower motors 11 and 37 from the power lines L1, L2 and L3.

A holding circuit is connected in shunt relationship with the start switch 58 which automatically operates to de-energize the control circuit and disconnect the compressor and blower motors 11 and 37. This circuit includes the normally open contacts 3CR1, actuated by the relay coil 3CR, which are serially connected with the parallel connected contacts 1TR1 of a time delay relay and the flow switch FLS previously mentioned. The contacts 1TR1 of the time delay relay are normally closed while the contacts of the flow switch FLS are normally open. As previously indicated, the flow switch FLS is interposed in the discharge conduit 31 of the oil pump 30 and is responsive to a minimum desired oil flow necessary for operation of the compressor. The flow switch FLS assures that oil is being continuously pumped into the compressor 10 and operates to deenergize the control circuit at any time the oil flow decreases to such an extent that it is below the minimum.

Connected in the control circuit in dependent relationship to the holding and start-stop circuits are the operating coils 1CR and 2CR for the magnetic motor contactors. Each coil, 1CR and 2CR, is connected in series with its respective serially-connected overload contacts, OL1 and OL2, OL3 and OL4. The coils 1CR and 2CR with their respective overload contacts are connected in shunt relationship and may be connected to the holding circuit through either a manually-actuated selector switch 60 or through the normally closed contacts 2TR1 of a time delay relay. The connection of the operating coils 1CR and 2CR to the holding circuit is made at the juncture of the parallel connected timer contacts 1TR1 and flow switch contact FLS whereby the relay contacts 3CR1 will be effective to control the operation of the blower and compressor

motors 11 and 37. The selector switch 60 is of the two-position type and is adapted to complete the circuit to the operating coils 1CR and 2CR in a first position and is open-circuited in the second. As will be noted from the circuit diagram, the selector switch 60 is connected in shunt relationship to the timer contacts 2TR1 and is effective to by-pass these contacts when in the first position. Interposed in the circuit of the operating coil 2CR are the contacts of the thermal switch TH2 previously mentioned. These contacts are of the normally-open type with the switch being set to close the contacts at about 120° F. and to open the contacts at about 110° F. The thermally-responsive element of the switch is installed in the oil cooler outlet conduit 33 and is effective to maintain the temperature of the oil within predetermined limits by controlling the operation of the oil cooler blower motor 37.

Also connected in shunt relationship to the operating coils 1CR and 2CR is the operating coil 1TR of the time delay relay. This relay is of the type wherein the contact action is retarded upon energization of the operating coil. In the present compressor system it has been determined that a delay of about 10 seconds time in opening of the contacts 1TR1 is desirable for optimum operation of the system. At any time the coil 1TR is deenergized, the coil and contacts 1TR1 will be instantaneously reset to their normal position.

An automatic free-unloading circuit is provided by this invention to simultaneously open the compressor high-pressure stage discharge to the atmosphere, by opening the valve S1 previously mentioned, and to close the unloader valve 16 preventing further intake of air. The free unloading circuit includes the solenoid-actuated valves S1 and S2. Selective energization of the solenoids of the valves S1 and S2 is effected through a pressure switch PS. This switch is responsive to the pressure in the air service conduit 25, through the connected conduit 45, and is of the single pole, double-throw type. In the first or low-pressure position, the pressure switch PS, the pole of which is also connected to the holding circuit so as to be in series with the relay contacts 3CR1, completes a circuit through the solenoid of the valve S1. In the second or high-pressure position, a circuit will be completed through the solenoid of the valve S2. The operating pressure limits of the switch PS, in the present embodiment, are set to maintain a circuit through the solenoid of the valve S1 at any time the pressure in the air service conduit 25 drops below 90 p.s.i.g. and to maintain a circuit through the solenoid of the valve S2 at any time the pressure in the air service conduit reaches 105 p.s.i.g.

Connected in parallel with the solenoid of the valve S2 is the operating coil 2TR of the second time-delay relay. This relay is operative to effect automatic start and stop of the compressor and blower motors 11 and 37 in accordance with the air pressure in the air service conduit 25. This relay is also of the type wherein the contact action is retarded upon energization of the operating coil. Since the coil 2TR is connected in parallel with the solenoid of the valve S2, it will be energized simultaneously therewith when the air service conduit pressure reaches 105 p.s.i.g. The contacts 2TR1 will not open, however, until the time delay of the relay has elapsed. At the expiration of the time delay, the contacts 2TR1 will open and deenergize the operating coils 1CR and 2CR causing the blower and compressor motors 11 and 37 to stop. The delay, which may be of the order of 15 minutes, has been found advisable in order that the number of starts will be limited to four in any one-hour time interval. This is necessary to prevent overheating of the compressor motor 11 due to the relatively large starting current. When the air service conduit pressure drops to 90 p.s.i.g. and deenergizes the solenoid of the valve S2, the timer coil 2TR will also be deenergized and will be reset in preparation for another timing interval. Simultaneously, with resetting of the operating coil 2TR, the contacts 2TR1 will

close permitting restarting of the compressor and blower motors 11 and 37.

As previously indicated, the conduit 18 is part of an oil scavenging system according to our invention which prevents the accumulation of oil in the manifold 14 during the unloaded operation of the compressor 10. This system is shown more in detail in FIGURE 3 and functions during the time the compressor is operating in the freely unloaded state. This scavenging system is an air-inspirating system which is connected to the manifold 14 and which operates on a pressure differential between the manifold and atmospheric air at the compressor intake to draw air from the atmosphere, during the unloaded cycle and to jet it through the manifold in the direction of normal flow through the manifold and thereby to scavenge the oil therefrom.

The bleed or drain conduit 27 running from the oil separator 24 also functions as a scavenging system during the unloaded operation of the compressor, as previously indicated. It also produces a jet of fluid through the manifold to prevent accumulation of oil therein.

The compressor air inlet is controlled by the valve 16 which may be a common type of unloading valve, an example of which is illustrated in FIGURE 3. It comprises a piston type valve member 66 which is actuated by receiver pressure reaching it through the conduit 41 controlled by the valve S2 previously mentioned. This valve member 66 is disposed in a housing 68 mounted on the low-pressure cylinder 12 over its inlet 15 and communicating therewith. The housing is provided with an inlet sleeve 70 leading thereto having a valve seat 69 at its inner end with which the valve member 66 cooperates. On the outer end of the inlet sleeve 70, the filter unit 17 is mounted. Atmospheric air will be drawn through the filter unit 17 and be filtered before it enters the housing 68 through the inlet sleeve 70.

During the normal operation of the compressor, the oil passing from the low-pressure cylinder 12 with the air will pass into the high-pressure cylinder 13 and out to the air receiver 21. During both the loaded and unloaded states of the compressor, the interstage manifold 14 will be at a much lower pressure than the oil separator 24. While the compressor is loaded, the oil passing from the low-pressure cylinder 12 with the air will pass into the high-pressure cylinder 13 and out to the air receiver 21. The compressed air flows from the receiver 21 into the separator 24 and any oil vapors remaining in the air are retained in the filtering elements in the oil separator and are passed from the separator into the drain or bleed line 27. The check valve 29 in the conduit 27 will prevent oil from being forced back up into the separator when the compressor is started. As soon, after starting of the compressor, as air pressure in the discharge end of the oil separator 24 exceeds the pressure in the manifold 14, any oil collected by the oil separator 24 will be forced into the manifold 14. The main stream of oil and air, as indicated, during loaded operation of the compressor will flow through the manifold 14 and there will be no tendency for oil to accumulate therein at this time. The oil and air returned from the separator 24 by the conduit 27 will merely be added to that main stream. However, the connection of the conduit 27 to the interstage manifold 14 according to our invention, will prevent the accumulation of oil in the manifold when the compressor is running unloaded. When the compressor is running unloaded, there is a tendency for oil to accumulate in the manifold since there is very little air in circulation within the compressor at this time, due to the fact that the unloading valve 16 is closed, and the oil flow into the compressor is maintained by the oil pump 30. It will be noted from the drawings that the conduit 27 is connected to the upstream end of the manifold preferably directly over the bottom wall thereof, as shown best in FIGURE 3, to direct the oil flow parallel to the bottom wall.

Without our scavenging system, if the compressor runs

for long periods unloaded, an excessive amount of oil will accumulate in the interstage manifold 14. Should there be a demand for additional compressed air subsequent to an accumulation of oil in the manifold thus returning the compressor to loaded operation, the accumulated oil will instantly be drawn into the high-pressure cylinder 13 and, if a sufficiently large volume of oil has accumulated, causes a hydraulic jam between the vanes of the high-pressure rotor. Such an accumulation of oil could damage or distort the vanes. Also, if the air compressor is a portable compressor and is used for work on very irregular terrain, the compressor may be operating at very steep angles which could possibly cause an excessive accumulation of oil in the lowest end of the manifold with resulting serious damage or breakage of the vanes of the rotor in the high-pressure cylinder. However, with the conduit, running from the separator 24, connected to the upstream end of the manifold 14, the oil and air mixture from the separator will be injected into the manifold toward the downstream end thereof. As will later appear, during the unloaded state of the compressor, the separator 24 will also be unloaded or connected to the atmosphere whereas the manifold will be at a lower pressure or vacuum. Therefore, air and oil will flow, because of this pressure differential, from the separator to the manifold. Thus, there is a jet of fluid created and directed through the interstage manifold 14 from the upstream end to its downstream end which is the normal direction of flow of the main stream of air and oil mixture, from the low-pressure cylinder 12 to the high-pressure cylinder 13. However, since during the unloaded state of the compressor there is no substantial flow of air through the manifold 14 from the low-pressure cylinder to the high-pressure cylinder but on the other hand there is a very low-pressure or vacuum condition in the manifold, which tends to cause accumulation of oil in the manifold, especially at the downstream end thereof, the jet of scavenging fluid created by our scavenging system and acting in the same direction as the normal flow through the manifold, will prevent the accumulation of oil therein.

According to our invention, we provide the conduit 18 as another means to prevent accumulation of oil in the interstage manifold 14 during the periods when the compressor is unloaded. This conduit 18 constitutes a piping system, between the interstage manifold and the air intake of the compressor, which provides for the inspiration of air through the intake filter 17 to the manifold 14 to produce a jet therein which will aid in forcing the oil from the manifold into the high-pressure cylinder 13. For this purpose, we connect the conduit 18 at one end to the unloading valve unit 16 and at its other end to the upstream end of the manifold 14. Thus, the inlet end 72 of the conduit 18, as shown in FIGURE 3, is connected to the valve unit 16 at the inlet sleeve 70 at a point intermediate the filter 17 and the valve seat 69. The air taken into the conduit 18 will, therefore, be filtered air. The other or outlet end 73 of the conduit is connected to the manifold 14 at its upstream end and directly above the bottom of the manifold adjacent the point where the outlet end 74 of the bleeder pipe or conduit 27 is also connected. The outlet ends 73 and 74 of the conduits 18 and 27 are directed toward the opposite or downstream end of the manifold 14. The conduit 18 is provided with a check valve 19 previously mentioned which closes when sufficient positive pressure develops in the manifold 14 to prevent flow from the manifold to the inlet of the unloader valve 16.

When the compressor is running in an unloaded state, very little air is in circulation within the compressor and even the bleeder conduit 27 from the oil separator furnishes only a small volume of air. Therefore, if it were not for the provision of our scavenging system, there could be a rapid buildup of oil in the interstage manifold 14. Since at this time the manifold 14 is under high vacuum, there is a substantial pressure differential between

the manifold and the compressor filter 17 which communicates with the atmosphere, it being understood that the unloading valve 16 is closed at this time. Also, at this time, as will later appear, the pressure side of the compressor is unloaded and there is no substantial pressure in the receiver 21 or the separator 24. The pressure differential between atmospheric air at the inlet and the low pressure in the manifold 14 is utilized, according to our invention, to inspire atmospheric air into said manifold and use it as a scavenger jet to act in a downstream direction on any oil tending to accumulate therein and to cause the oil to flow toward and into the high-pressure cylinder 13.

Thus, with this arrangement, since the unloader valve 16 is totally closed when the compressor is running in an unloaded state, air will be inspired from the chamber in the sleeve 70 between the valve seat 69 and the intake filter 17. Consequently, only filtered air is drawn into the interstage manifold 14 through the conduit 18. This inspired air is drawn into the manifold 14 along the bottom thereof thereby aiding in moving oil therein from the low-pressure cylinder discharge to the high-pressure cylinder intake. When the compressor re-assumes the pumping load, the valve 16 is opened by atmospheric pressure since holding pressure has been exhausted from the conduit 41, a positive pressure develops in the manifold 14 and the check valve 19 is closed thereby preventing air and oil flow-back through the conduit 18 into the compressor intake.

Thus, both the conduit 27 from the oil separator 24 and the conduit 18 from the unloader valve 16 will function, during the unloaded state of the compressor, to create jets of fluid injected at the downstream end of the manifold 14 and directed toward the upstream end thereof in the direction of normal flow therethrough. These jets will scavenge from the manifold any oil which tends to accumulate therein during the unloaded operation of the compressor.

The operation of the oil-scavenging system of this invention has been described above in detail. This system will function whenever the compressor is operating unloaded.

The general operation of the compressor and especially as it relates to the free-unloading operation is briefly described herein as related to the schematic diagrams of FIGURES 1 and 2. In these diagrams, the several elements or components are shown in their normal positions as when the compressor system is not operating. In this condition, the disconnect switch 55 will be open and the pressure in the air service conduit 25 may be at atmospheric pressure or at least below the minimum desired operational pressure of the system. The exhaust valve S1 will be open since its solenoid will be deenergized. Also, the solenoid of the control valve S2, which is deenergized, will be positioned as shown to exhaust or vent the conduit 41 to the atmosphere. The unloader valve 16 will thus be in its normally open position as the actuating air cylinder is not pressurized. Since the temperature of the lubricating and cooling oil in the system will be below the minimum desired for operation, the thermal by-pass valve 40 will be positioned by its thermal element to connect the conduit 38 from the oil reservoir 23 to both lines 38 and 39. In the following description of the operation, it is to be assumed that the selector switch 60 will be placed in the open position denoted as "AUTO" for automatic start-stop operation as well as automatic free-unloading. As will be apparent from the electrical circuit of FIGURE 2, placing the selector switch 60 in the closed position denoted "CONT. RUN" will eliminate the automatic start-stop features of the system but not the free-unloading operation.

Initial starting of the compressor system is preceded by closing the disconnect switch 55 which will energize the control circuit transformer 57 and the control circuit connected thereto and also connect the contactors of the com-

pressor motor 11 and the blower motor 37 to the power source. Subsequent to closing of the disconnect switch 55, the start switch 58 is momentarily depressed to complete the starting circuit as has been previously described in detail and cause relay contacts 3CR1 to close. While the compressor motor 11 will be immediately started, the blower motor 37 will not start until the temperature of the oil in the system has risen to a desired maximum, 120° F. for example, causing switch TH2 to close. A subsequent decrease in the oil temperature to a predetermined value, such as 110° F., will cause switch TH2 to open and the temperature of the oil will be maintained within the desired limits.

Since the pressure in the air service conduit 25 at the time of initially starting will be below the minimum operational pressure, which may be 90 p.s.i.g., switch PS will be maintained in its first position energizing the solenoid of the exhaust valve S1. When thus energized, valve S1 will be closed, preventing further flow of air through conduit 51, permitting a build-up of pressure in the air receiver 21 and connected tanks and conduits. Continued operation will permit the oil pump 30 to induce an oil flow through conduit 31 into the oil gallery 32 of the compressor 10. After establishment of a minimal oil flow, the flow switch FLS will be actuated closing its contacts and thus by-pass contacts 1TR1. The contacts 1TR1 will remain by-passed as long as oil is flowing through conduit 31 for proper cooling and lubrication of the compressor 10. Simultaneously with starting the compressor 10, the operating coil 1TR of the time delay relay will be energized and will open its associated contacts 1TR1 after a predetermined time interval of, for example, five to ten seconds. Opening of the contacts 1TR1 places continued operation of the compressor system under control of the flow switch FLS. At any subsequent time, should the oil flow from the pump 30 be insufficient for cooling and lubrication, the flow switch FLS will open to deenergize relay coil 3CR causing contacts 3CR1 to open and thus disconnect the remainder of the control circuit from the transformer 57.

Assuming that the compressor 10 and its oil pump 30 are operating normally, air will be drawn through the air-intake filter 17 and the open unloader valve 16 into the low-pressure stage 12 of the compressor during a loaded operational cycle. The air will be compressed and discharged through the conduit 20 into the air receiver 21 and other connected tanks and conduits to build up the compressed air supply. The contacts of the pressure switch PS will remain in the illustrated first position during loaded operation of the compressor 10 for a continued supply of compressed air. A loaded operational cycle will continue as long as there is a continued demand for compressed air and the pressure in the air service conduit 25 does not reach the maximum operating pressure which may be about 105 p.s.i.g.

When the compressed air requirements have been fully met, or the capacity of the compressor is such that the output thereof exceeds the current requirements, the compressor system of this invention will automatically revert to free-unloaded operation to minimize power consumption. In the usual compressed air systems where the maximum desired operational pressure may be approximately 105 p.s.i.g., the pressure switch PS is set to be actuated at this maximum pressure and the pole thereof will be switched to the second position to energize the solenoid of valve S2. Simultaneously, the solenoid of valve S1 will be deenergized and this spring-biased valve will be opened thus venting the conduit 51 to the atmosphere through the exhaust silencer 59, thereby venting the receiver 21 and associated tanks 23 and 24 which are the major elements of the compressor unit receiver system. Energization of the solenoid of valve S2 causes displacement of the movable member thereof to connect the conduit 44 to conduit 41. Pressurization of the air pilot actuator of the unloader valve 16 is thus effected as the

pressure in conduit 41 will be that of the air service conduit 25 to which conduit 44 is connected and the air may flow freely through the check valve 42 into the air pilot actuator of the unloader valve 16. The unloader valve 16 will thus be closed preventing further flow of air into the low-pressure stage 12.

Free-unloaded operation of the compressor 10 with the unloader valve 16 closed and the high-pressure side of the compressor opened to the atmosphere through the air receiver 21, separator 24 and conduit 51 will continue until the pressure in the air service conduit 25 has dropped to the minimal operating pressure of approximately 90 p.s.i.g. At this pressure, the switch PS will be reset to its first position for further loaded operation, as previously described. Valve S1 will accordingly be actuated to close conduit 51 and the control valve S2 will return to its normal position closing conduit 44 to the intake valve pilot actuator, venting conduit 41 to the atmosphere. The pressurized air within the actuating cylinder of the unloader valve 16 will exhaust through the restricted by-pass 43 and conduit 41 to the atmosphere. The restricted by-pass 43 prevents instantaneous operation of the unloader valve 16 for protection of the valve and the compressor 10.

During this free-unloaded operation of the compressor, the scavenging system including both of the jets produced by the lines 18 and 27, as previously described, and directed into the manifold 14 will function to prevent accumulation of oil in the manifold.

An automatic starting and stopping circuit is also incorporated in the compressor system, as previously indicated. During free-unloaded operation, the operating coil 2TR of the second time delay relay will be simultaneously energized with the solenoid of valve S2. This time delay relay, which may have a delay of approximately 15 minutes in the actuation of its contacts 2TR1, will control the stopping of the compressor motor 11 and blower motor 37. The timing interval begins at the start of the free-unloaded cycle and the contacts 2TR1 will open at the expiration of this timing interval. Upon opening of contacts 2TR1, the operating coils 1CR and 2CR of the motor contactors and the operating coil 1TR of the first time delay relay will be disconnected from the circuit. Contacts 1TR1 will instantaneously close and the flow switch FLS will subsequently open when the oil flow through conduit 31 has sufficiently decreased. At any subsequent time that the pressure in the air service conduit 25 decreases to 90 p.s.i.g., switch PS will be reset, deenergizing the solenoid of valve S2 and the operating coil 2TR of the time delay relay. Contacts 2TR1 of this relay will be instantaneously closed to reconnect coils 1CR and 2CR and 1TR into the circuit. The compressor motor 11 and blower motor 37 will thus be restarted, as previously described, in conjunction with the initial starting phase.

It will be apparent from the above that our invention provides in an internally oil-cooled, positive displacement type rotary compressor, means for greatly reducing the power required to run the compressor in an unloaded state, that is, when it is not pumping a substantial volume of fluid at an elevated pressure. The unloading of the intake side of the compressor is accomplished at the intake valve whereas the unloading of the pressure or receiver side of the compressor is accomplished by venting the air therefrom at a point where the air is sufficiently free from oil to allow it to be exhausted to the atmosphere without a loss of circulating oil. Thus, the power to drive the rotors during the unloaded state of the compressor is greatly reduced. Furthermore, this invention provides oil scavenging means which functions in association with the unloading system for preventing the accumulation of oil in the interstage manifold which otherwise might cause damage to the rotors. The control system for the unloading and loading operations as well as all other operations of the compressor are completely automatic.

This control system includes timing means which limits the number of starts of the electric motors to prevent damage thereto.

The oil tank 23, the receiver 21 and the separator 24 are shown as separate tanks but it is to be understood that the oil could collect in the bottom of the receiver tank so that the separate oil tank could be eliminated. Also, the oil separator tank could be disposed within the receiver tank. Our free unloading system and the associated oil scavenging system would work equally as well with such modifications of the compressor system. 10

According to the provisions of the patent statutes, the principles of this invention have been explained and have been illustrated and described in what is now considered to represent the best embodiment. However, it is to be understood that, within the scope of the appended claims, the invention may be practiced otherwise than as specifically illustrated and described.

Having thus described our invention, what we claim is:

1. A rotary compressor comprising low-pressure and high-pressure stages having air-compressing rotors, a pressure lubricating-cooling system for said stages and connected thereto for supplying oil thereto, an inlet valve 20 controlling the inlet of air to be compressed into said low-pressure stage, an air and oil receiver system connected to the discharge of said high-pressure stage for receiving the oil and air mixture discharged thereby, said receiver system including separator means for separating the oil and air of the mixture, said separator means having an inlet for the mixture, an outlet means for the air and an outlet means for the oil for returning it to said stages, a venting unloading valve connected to said separator air outlet means of the receiver system, said receiver system including a service line leading therefrom and connected to said separator air outlet means thereof, a check valve in the service line for preventing venting of said line upon opening of said venting unloading valve in the receiver system, and control means connected to both of said valves for closing the inlet valve and opening the venting unloading valve to freely unload the compressor, said control means comprising a pressure line connected to said service line and to said inlet valve for actuating it to close said inlet valve when pressure in the service line reaches a selected upper limit and thereby to unload the inlet side of the compressor. 45

2. A rotary compressor according to claim 1 in which said receiver system venting valve is an electrically-actuated valve and said inlet valve is controlled by a second electrically-actuated valve, and an electric circuit connected to both of said electrically-actuated valves for simultaneously opening the venting valve and closing the inlet valve. 50

3. A rotary compressor according to claim 2 wherein each of said valves includes an electromagnetic solenoid for actuation thereof and said electric circuit includes a power source and switch means connected in circuit with said power source and said valve solenoids to control the operation of said valves, said switch means being of the pressure-actuated type having a pressure-responsive element which is pneumatically connected to said service line for actuation of said switch in accordance with the pressures in said service line. 55

4. A rotary compressor according to claim 3 wherein said switch is operative to cause closing of said venting valve and opening of said inlet valve when the pressure in said service line reaches a predetermined low level and to cause opening of said venting valve and closing of said inlet valve when the pressure in said service line reaches a predetermined high level. 65

5. A rotary compressor according to claim 2 wherein said air-compressing rotors are provided with a drive motor and said electric circuit includes control apparatus for selectively starting or stopping said rotor drive motor, said control apparatus having an electromagnetic solenoid operable on energization thereof to start the said rotor 70

drive motor and operable on deenergization thereof to stop the said rotor drive motor, and timer-actuated switch means connected in said electric circuit to deenergize said control apparatus solenoid at a predetermined time subsequent to the pressure in said service line reaching and being maintained at said predetermined high level for said predetermined time.

6. A rotary compressor according to claim 2 wherein said lubricating-cooling system includes a heat-exchanger having a drive motor and said electric circuit includes means for selectively starting or stopping said heat-exchanger drive motor, said means including thermal switch means responsive to the temperature of the lubricating-cooling medium in said lubricating-cooling system.

7. A compressor according to claim 1 in which the low-pressure stage is connected to the high-pressure stage by an interstage manifold, and means for scavenging oil from the manifold, said means comprising a fluid line connected to said manifold at the upstream end thereof and connected to a source of fluid under greater pressure than that in the manifold during the unloaded state of the compressor.

8. A compressor according to claim 1 in which the low-pressure stage is connected to the high-pressure stage by an interstage manifold, and means for scavenging oil from the manifold, said means comprising an air line connected to atmosphere when said inlet valve is closed, and connected to said manifold at the upstream end thereof.

9. A compressor according to claim 1 in which the low-pressure stage is connected to the high-pressure stage by an interstage manifold, said receiver system comprising a receiver tank and an oil separator connected thereto, means for scavenging oil from the manifold, said means comprising a fluid line leading from the oil separator and being connected to said manifold at the upstream end thereof. 35

10. A compressor according to claim 6 in which the scavenging means also includes an air line connected to atmosphere when said inlet valve is closed and connected to said manifold at the upstream end thereof.

11. A rotary compressor having a fluid inlet system and a fluid receiver system with fluid-compressing means connected therebetween and having a discharge outlet, a pressure-lubricating-cooling system for said compressing means and connected thereto to supply lubricating and cooling oil thereto, said inlet system including unloading means for unloading the compressing means, said receiver system including separator means which receives air and oil mixture discharged from said discharge outlet of said compressing means for separating the oil and air of the mixture, said separator means having an inlet for the mixture, an outlet means for the air and an outlet means for the oil for returning it to said compressing means, a venting unloading means connected to said separator air outlet means, and control means connected to both of said unloading means for actuating them simultaneously. 45

12. A rotary compressor having a fluid inlet system and a fluid receiver system with fluid-compressing means connected therebetween and having a discharge outlet, a pressure-lubricating-cooling system for said compressing means and connected thereto to supply lubricating and cooling oil thereto, said inlet system including unloading means for unloading the compressing means, said receiver system including a separator means which receives air and oil mixture discharged from said discharge outlet of said compressing means for separating the oil and air of the mixture, said separator means having an inlet for the mixture, an outlet means for the air and an outlet means for the oil for returning it to said compressing means, a receiver system venting unloading means connected to said separator air outlet means, said receiver system including a service line leading therefrom and connected to said separator air outlet means, a check valve in the service line for preventing venting of said line upon opening of said receiver system venting unloading means, and con- 75

trol means connected to both of said unloading means for actuating them simultaneously.

13. A rotary compressor having a fluid inlet system and a fluid receiver system with fluid-compressing means connected therebetween and having a discharge outlet, a pressure-lubricating-cooling system for said compressing means and connected thereto to supply lubricating and cooling oil thereto, said inlet system including unloading means for unloading the compressing means, said receiver system including a separator means which receives air and oil mixture discharged from said discharge outlet of said compressing means for separating the oil and air of the mixture, said separator means having an inlet for the mixture, an outlet means for the air and an outlet means for the oil for returning it to said compressing means, a receiver system venting unloading means connected to said separator air outlet means, said receiver system including a service line leading therefrom and connected to said separator air outlet means, a check valve in the service line for preventing venting of said line upon opening of said receiver system venting unloading

means, and control means connected to both of said unloading means for actuating them simultaneously, said control means comprising a pressure line connected to said service line and to pressure-type actuating means for both of said unloading means.
